UNITED STATES PATENT OFFICE.

GLEN O'BRIEN, OF MANHATTAN, KANSAS.

DEHUMIDIZER.

1,143,061.

Specification of Letters Patent. Patented June 15, 1915.

Application filed March 7, 1914. Serial No. 823,135.

To all whom it may concern:

Be it known that I, GLEN O'BRIEN, a citizen of the United States, and a resident of Manhattan, State of Kansas, have invented 5 certain new and useful Improvements in Dehumidizers, of which the following is a full and exact specification.

This invention relates to dehumidizers and has for its principal object to provide 10 a device of this character which is of simple and inexpensive construction, easily maintained, and effective at all times not only to preserve the air of a room at a suitably dry and low temperature but which also purifies 15 the air within a room despite the exhalations of the occupants thereof.

Other objects will appear as the invention is more fully described and explained in the following specification, illustrated in the accompanying drawings and pointed out in 20 the appended claim.

In the drawings, Figure 1 is a longitudinal sectional view of my device. Fig. 2 is an end elevation of the same, with parts 25 broken away and other parts in section. Fig. 3 is a face view of the screen and its frame. Fig. 4 is an enlarged detail fragmentary view of one of the pipes. Fig. 5 is a similar sectional view showing a modified 30 form of the arrangement of pipes within the casing.

Referring now more particularly to the drawings, reference numeral 1 designates a container which, in this instance, is in the 35 form of a hollow cylinder and through the upper surface of which are apertures 2, which communicate with a chamber whose outlines are marked by the top surface 4 and end and side walls 5 and 5^a, respectively, 40 the said walls being secured to the said container by any suitable means such as machine screws indicated at 6, and at one end of the said chamber is a pipe 7 which is adapted to communicate with any suitable 45 source of water supply. The forward end of the said container may be supported upon legs such as indicated at 18, and its rear end supported by an offset 50 9. and at the bottom of the said container is an outlet pipe 10. At about the midsection 55 of the said container is an annular internal flange 11, and at the right-hand end (see Fig. 1.) is a similar flange 12 and against the last-mentioned flange may be a 60 circular frame 13 within which is a screen 14. Within the said container is a plurality 65

of pipes, indicated at 15, and around each end of each of which is a bead 17, the function of which is to hold each of the said pipes in spaced relation to its adjacent pipes. 60 Within the left-hand end, (see Fig. 1) of the said container is a fan 18 whose spindle 19 is revolvably supported within a bearing 20 the radially projecting arms 20^a of which are secured at 21 to the interior of the said 65 container.

22 indicates a motor upon whose central shaft is affixed a pulley 23 which is connected by means of a belt 23^a to a similar pulley 24 affixed to the spindle 19. 70

From the foregoing, it will be seen that if the fan 18 be set in motion and water allowed to pass through the apertures 2, from the chamber already described to the interior of the container 1, the water will 75 run down over the pipes 15, and the air from the room will be meanwhile either drawn or forced through the said container, the water passing out through the pipe 10 from the lower side of the container: that 80 the relatively warm air of the room thus drawn or forced through the said container, due to the cooling effect of the water and the relatively large surface presented by the pipes 15, will be reduced in temperature 85 and most of the impurities in the air will pass out with the water through the pipe 10, the function of the screen 13 being to arrest the floating impure atoms in the air which are of considerable size, as the air 90 passes through the screen. As above indicated, the fan which I have shown at 18 may operate either to force the air through the container or to draw the air through it. 95

In Fig. 5 the container and all other portions of the device are the same as already described, but, instead of the longitudinally disposed pipes, 15 metallic rings such as indicated at 25 may be used and held in spaced relation to each other by any suitable means 100 such as screens indicated at 26. The function of the pipes is, of course, to present as large a cooling surface as possible, however they may be arranged, and it is obvious that a relatively large cooling surface could be obtained by the use of coarse gravel and the like. 105

While I have shown and described a particular form of embodiment of my invention, I am aware that many changes therein 110 will readily suggest themselves to others skilled in the art without departing from

the spirit and scope of my invention, and I therefore desire to avoid being limited to the exact form shown and described except as limited in the appended claim.

5 Having fully described my invention, what I claim as new and desire to protect by Letters Patent is:—

In a device of the class described, the combination with a cylindrical container having inlet and outlet tubes and a chamber 10 at its upper surface which communicates with the inlet tube, of apertures in the said

container which communicate with the said chamber, a plurality of pipes within the said container, a bead upon each of the pipes 15 for holding the pipes in spaced relation to each other, a screen within one end of the container and a fan at the opposite end thereof.

GLEN O'BRIEN.
